UNITED STATES PATENT OFFICE

ALLAN F. HUNT, OF SAN FRANCISCO, CALIFORNIA

BOOK HANGER

Application filed March 10, 1928, Serial No. 260,632. Renewed August 25, 1930.

The present invention relates to hangers and is adapted particularly for use in hanging telephone directories and similar books from a conveniently disposed hook, nail or other attaching device, extending from the wall adjacent the telephone.

An object of the invention is to provide a hook hanger of this character, embodying adjustable means for accommodating the books of varying thicknesses.

A still further object of the invention is to provide an attachment of this character, of a simple and practical construction, which is strong and durable, neat and attractive in appearance, which at the same time serves as a protector for the bound edge of the book, relatively inexpensive to manufacture, and otherwise well adapted to the purpose for which the same is intended.

Other objects and advantages of the invention will become apparent during the course of the following detailed description, taken in connection with the accompanying drawings, forming a part hereof, and in which:

Figure 1 is a perspective view showing the hanger in book supporting position.

Figure 2 is a front elevational view thereof, and

Figure 3 is a transverse sectional view, through the sliding connection provided for the sections composing the hanger.

Referring now to the drawing in detail, the invention comprises a book hanger including an attaching plate 5, having an opening 6 formed in one end thereof, by means of which the plate may be fitted over a hook, nail or the like 7, for supporting the plate against the wall or other object from which the hook or nail 7 extends.

At one of the side edges of the plate 5, remote from the opening 6 is formed an arm 8 extending outwardly from the plate at right angles thereto, said arm being slidably carried within a channel shaped guide 9, having its upper and lower edges arranged in overlapping relation with respect to the edges of the arm and comprising flanges 10 to prevent displacement of the arm with respect to the guide.

The end of the guide 9 is disposed outward

ly from the plate 5 and is formed into an extension 11, arranged parallel with respect to the plate and from the lower edge of said extension is formed a book edge protecting member 12 extending downwardly with respect to said plate.

A bolt 13 extends between the plate 5 and the extension 11, in spaced relation with respect to the plate 8 and associated guide 9, the threaded end of the bolt being extended outwardly from the extension 11 and provided with a tightening nut 14.

The bolt 13 is adapted to be inserted through the opening usually formed at the upper bound edge of a telephone directory so that the directory will be secured between the plate 5 and extension 11 as indicated by the dotted lines 15 shown in Figure 1 of the drawing. When so arranged, the member 12 will be disposed against the outermost bound edge of the book and in this manner will serve as a protection for the edge thereof. By securing the bound edge of the book between the plate 5 and extension 11, in the manner indicated, the book may be hung from a hook or nail, such as shown at 7, in a position flat against a wall or other vertical surface, in an out-of-the way position. The manner of slidably connecting the arm 8 and guide 9 formed on the respective members of the hanger will permit directories of various thicknesses to be firmly secured between the plate 5 and the extension 11 of the device.

It is obvious that the invention is susceptible of various changes and modifications, without departing from the spirit or scope of the invention or sacrificing any of its advantages, and I accordingly claim all such forms of the device to which I am entitled.

Having thus described my invention, what I claim as new is:

A book hanger comprising a book edge clamping member composed of a pair of telescoping plates disposed transversely of the bound edge of the book, one of said plates having a laterally disposed extension provided with an opening for receiving a wall attached fixture, a lateral extension formed on the other of said plates and extending oppositely from said first named extension.

and parallel with the bound edge of the book
for reinforcing the same, and a bolt connect-
ing said extensions and inserted transversely
through the book for securing the extensions
in clamping position at opposite sides of the
book.

In testimony whereof I affix my signature.
ALLAN F. HUNT.
